(57) **CLAIM**

The ornamental design for a hose storage apparatus, as shown and described.

DESCRIPTION

FIG. 1 is a front view of a hose storage apparatus showing my new design.

FIG. 2 is a rear view thereof;

FIG. 3 is a left side view thereof;

FIG. 4 is a right side view thereof;

FIG. 5 is a bottom view thereof;

FIG. 6 is an overhead view thereof;

FIG. 7 is a bottom and rear perspective view thereof; and,

FIG. 8 is a top and front perspective view thereof.

The broken lines are for the purpose of illustrating portions of the article and form no part of the claimed design.

1 Claim, 7 Drawing Sheets(56)
